UNITED STATES PATENT OFFICE.

ROBERT LEE BURNS AND GEORGE IRWIN KENISTON, OF TAFT, CALIFORNIA.

CEMENT-DUMP BAILER FOR OIL-WELLS.

1,275,378.

Specification of Letters Patent. Patented Aug. 13, 1918.

Application filed May 20, 1918. Serial No. 235,683.

To all whom it may concern:

Be it known that we, ROBERT LEE BURNS and GEORGE IRWIN KENISTON, citizens of the United States, residing at Taft, in the 5 county of Kern and State of California, have invented certain new and useful Improvements in Cement-Dump Bailers for Oil-WellS, of which the following is a specification.

10 Our invention relates to dump-bailers used in the well-boring art, to convey cement or other material to the bottom of oil-wells without subjecting it to liability of admixture with the well fluids while being lowered 15 therein, and to leave the cement or other substance at the bottom of the well when the bailer is withdrawn.

The object of our invention is to provide a simple and effective device of this character, 20 adapted to safely carry and protect its contents while being lowered, and to automatically open when it reaches the bottom of the well in order to dump said contents as it is being lifted therefrom.

25 To this end our invention consists in the novel dump-bailer which we shall now fully describe by reference to the accompanying drawings in which.

Figure 1 is an elevation of our dump-bailer, showing it in position for its dumping function after having been opened by reaching the bottom of the well and just starting to be withdrawn.

Fig. 2 is a vertical section of the same 35 showing it closed for its conveying function while being lowered into the well.

A is a body member consisting of a collar provided with an internal thread at each end. One end of the collar is intended to 40 be screwed upon the end of one or more joints of pipe or casing A' which forms a container member of sufficient capacity to hold the quantity of cement or other material which it is desired to place in the well. 45 The other end of the collar is connected to the cylinder or barrel member B of the device.

This barrel is provided with external threads at its upper end, which are screwed 50 into the collar A. The lower end of the barrel is closed by a bottom B' of larger external diameter than that of the body of the barrel so that it projects peripherally to form a stop for the valve member herein- 55 after mentioned. A discharge outlet here

shown as two holes C are provided near the bottom of the barrel.

D is a sleeve valve member sliding upon the barrel B and provided with a stem member, here shown in the form of reins E which 60 extend below the bailer through slots in the rim of the bottom B' of the barrel, and terminate in a perforated cross foot E'.

A spring latch F is inserted in the barrel B in such a way that when the sleeve valve 65 D has been raised sufficiently to clear the holes C as shown in Fig. 1, it will be caught by the top of the latch and prevented from again closing the holes until the latch is pressed in flush with the barrel. 70

In operation, the sleeve valve D is brought to the position shown in Fig. 2, in which position it covers the holes C and prevents the escape of material from the inside of the bailer. The bailer is then filled with ce- 75 ment or other material to be placed in the well, and lowered to the bottom. When the bailer reaches the bottom of the well the foot E' of the reins E rests upon the bottom and arrests the descent of the sleeve valve D so 80 that the barrel B slides down through said sleeve valve until the spring latch F is released, thus holding the sleeve valve clear of the holes in the bottom of the bailer, as shown in Fig. 1. When the bailer is raised 85 its contents are discharged through the holes C and remain at the bottom of the well.

We claim:

1. A cement dump-bailer for the described purpose comprising a body-member; a container-member fitted to one end of the body-member; a barrel member fitted to the other end of the body-member, said barrel-member having a discharge outlet; a valve-member adapted to control said outlet; a valve- 90 stem connected with the valve-member and disposed by contact with the well bottom to move said valve member to open the discharge outlet; and a latch acting on the valve-member to hold it open. 95

2. A cement dump-bailer for the described purpose comprising a body-member; a container-member fitted to one end of the body-member; a barrel-member fitted to the other end of the body-member, said barrel member 100 having a discharge outlet; a sleeve-valve fitted to and slidable upon the barrel-member to cover and uncover the discharge outlet thereof; a stem member connected with the sleeve-valve and extending beyond the 110

barrel member, adapting it by contact with the well bottom to lift the sleeve-valve, to uncover the barrel outlet; and a latch acting on the sleeve-valve to hold it open.

- 5 3. A cement dump-bailer for the described purpose comprising a body-member; a container-member fitted to one end of the body-member; a barrel-member fitted to the other end of said body-member, said barrel member having a closed bottom projecting peripherally, and having also a discharge outlet in its wall above said closed bottom; a sleeve-valve fitted to and slidable upon the barrel-member between its bottom and
10 the body-member, to cover and uncover the discharge outlet; a stem-member connected
15

with the sleeve-valve and extending beyond the bottom of the barrel-member adapting it, by contact with the well bottom, to lift the sleeve-valve to uncover the barrel outlet; 20 and a spring latch carried by the barrel-member and acting on the sleeve-valve to hold it open.

In testimony whereof we have signed our names to this specification in the presence of 25 two subscribing witnesses.

ROBERT LEE BURNS.
GEORGE IRWIN KENISTON.
